Harold Con Roberts

INVENTOR

BY Victor J. Evans

ATTORNEY

J. L. Wright

WITNESS:

UNITED STATES PATENT OFFICE.

HAROLD CON ROBERTS, OF KENDALLVILLE, INDIANA.

CHECK VALVE.

Application filed January 15, 1924. Serial No. 686,373.

To all whom it may concern:

Be it known that I, HAROLD CON ROBERTS, a citizen of the United States, residing at Kendallville, in the county of Noble and State of Indiana, have invented new and useful Improvements in Check Valves, of which the following is a specification.

This invention relates to improvements in radiators for internal combustion motors, the general object of the invention being to provide means for preventing wasting of the water through the overflow pipe, while preventing any pressure from accumulating in the radiator.

This invention also consists in certain other features of construction and in the combination and arrangement of the several parts, to be hereinafter fully described, illustrated in the accompanying drawing and specifically pointed out in the appended claim.

In describing my invention in detail, reference will be had to the accompanying drawing wherein like characters denote like or corresponding parts throughout the several views, and in which:

Figure 1 is a view of a radiator showing my invention in use.

Figure 2 is a longitudinal sectional view showing a slight modification of the invention.

Figure 3 is a section on line 3—3 of Figure 2.

Figure 4 is a longitudinal sectional view through the device shown in Figure 1.

Figure 5 is a view similar to Figure 2 but showing the valve seat member used as a valve.

Figure 6 is a section on line 6—6 of Figure 5.

As shown in Figures 1 and 4 I provide a tube 2 which is slipped over the upper end of the overflow pipe and which has its upper end threaded to receive the lower part

of the housing 3. If desired, the upper end of the overflow pipe itself may be threaded to receive this housing as shown in Figures 2 and 5. A cage 4 is arranged in the housing with its flanged upper end engaging the top part of the housing, and a spring 5 and ball seat 6 are arranged in said cage. A threaded cap 7 closes the upper end of the hous-

ing and this cap is formed with a ball seat 8 for receiving the ball valve 9 which is normally pressed upon the seat 8 by the spring 5.

It will thus be seen that the overflow pipe is normally closed so that water cannot escape therethrough, but as soon as any pressure occurs in the radiator due to the expansion of the water by heat or the formation of steam in the radiator, the ball 9 is forced downwardly against the slight pressure of the spring 5 so that the pressure is removed from the radiator. As soon as the pressure is relieved, the valve will close and prevent the escape of any more water.

I prefer to make the ball seat 6 with the cone-shaped lower part 10 so that by turning this seat over it can be used in place of the ball valve 9, as shown in Figure 5. The spring will then engage the flat part of this member to hold it against the seat on the cap. This invention will save water by preventing it from escaping down the overflow pipe when the car is going down a steep grade or when the car comes to a sudden stop which causes the water to rush to the top of the radiator. This device will also prevent the rapid evaporation of alcohol or other anti-freezing solutions by preventing the escape of the vapors through the overflow pipe. This invention is especially valuable in desert countries and other dry places. It is also useful in mountainous districts where much water is lost by the vehicle traveling down steep grades.

By use of the cage if the spring should break, the ball cannot drop down and close the overflow pipe which might cause the radiator to burst. The ball seat 6 permits the ball to have free movement so that it will make a perfect seat on the cap and this seat 6, can be turned over and used as a valve in place of the ball. The spring tension can be adjusted by placing shims 12 between the cage and the screw cap as shown in Figure 5.

It is thought from the foregoing description that the advantages and novel features of my invention will be readily apparent.

I desire it to be understood that I may make changes in the construction and in the combination and arrangement of the several parts, provided that such changes fall within the scope of the appended claim.

Having described the invention, I claim:—

A check valve comprising a housing adapted to be connected with the upper end of a pipe, a screw cap on the housing having an opening therein, a ball valve closing the opening, a cage in the housing, a spring carried thereby and a ball seat supported by

the spring and engaging the ball valve, said seat having a conical lower part which is arranged to take the place of the ball valve 10 when desired.

In testimony whereof I affix my signature.

HAROLD CON ROBERTS.
